UNITED STATES PATENT OFFICE.

WILLIAM C. HERBERT, OF NEW YORK, N. Y.

GARMENT SUPPORTER.

Application filed July 25, 1925. Serial No. 46,098.

This invention relates to supports for trousers or skirts, though it is noted that the invention is not limited to supports for these particular garments, nor in some respects even to garment supports.

The inventive features for the accomplishment of the objects mentioned below are shown herein in connection with an improved garment support which, briefly stated, includes a body encircling means; upwardly extended supports having the lower part supported on said means; and means whereby trousers are supported on the upper ends of the supports.

One object of the invention is to provide a device of this kind which will support the waist of the garment well above the hip line of the wearer.

Another object of the invention is to provide a device of this kind having the body encircling means anatomically contoured and very comfortable in use.

Another object of the invention is to provide a device of this kind in which the supports are removable and interchangeable for different heights of waist line, the ends of the supports being received in pockets on the encircling means and in the waist of the garment.

Other objects of the invention are to improve generally the comfort, simplicity, convenience and efficiency of such devices and to provide a device of this kind which is washable, durable, economical to manufacture and wear and which will not get out of order.

Still other objects of the invention will appear as the description proceeds; and while herein details of the invention are described, the invention is not limited to these since many and various changes may be made without departing from the scope of the invention as claimed.

Less briefly stated, the device includes an abdominal supporter of anatomical contour comprising right and left members having at the rear and front end portions means whereby the supporter may be adjustably secured around the wearer, each of said members comprising front and rear portions of canvas, an intermediate portion of open-work fabric having its lower edge arched to substantially fit over the hip, and a hip portion of elastic webbing over the hips and joining said edge. Pockets secured on each member and pockets on an upper band se-

cured to the inner face of the waist of the garment to receive the lower and upper ends respectively of flat, flexible, upright supports of bone, celluloid or the like, for supporting the garment above the hip line.

In the accompanying drawing, showing by way of example, one of many possible embodiments of the invention,

Fig. 1 is an outer face elevation showing the abdominal supporter removed from the wearer and extended out flat;

Fig. 2 is a face elevation showing the upper band extended;

Fig. 3 is a fragmental side elevation showing the support on the wearer; and

Fig. 4 is a fragmental front perspective view showing the upper band attached to the garment.

The body encircling means comprises an abdominal supporter of washable fabric of anatomical contour adapted to fit around and over the hip to give comfort and support to the abdominal region and comprising right and left members 10 and 11, having lacing eyelets 12 along the rear edge receiving lacings 13, and pairs of upper and lower snap eyelets 14, buttonholes or the like at the front end portion of one of the members and a pair of snap studs 15, buttons or the like on the outer face of the front end portion of the other, whereby the supporter may be adjustably buttoned around the wearer.

Each of said members comprises a front portion 20 and a rear portion 21 of one or two ply canvas, or other suitable material, these front and rear portions being connected by the intermediate portion 22 of ventilating open-work fabric having its lower edge 23 upwardly arched to substantially fit over the hip and extend as far down as 24 to the front and rear of the hip, the semi-circular hip portion 25 of elastic webbing being secured at its upper edge to said edge 23 and curving at its free lower edge 100 downwardly for fitting over and substantially conforming to the hip, so that downward movement of the supporter due to pressure on the bottoms of the upwardly open pockets 30, later described, of the supporter 105 will be prevented by engagement of said intermediate portion 22 and hip portion 25 with the hip.

Upwardly opening patch pockets 30 are stitched to the outer face of each of said members just to the front and rear of said hip portions and extend substantially to the

top edge of said members and receive the lower curved ends 31 of a plurality of interchangeable cleanable flat flexible, semi-rigid, supports 32 of celluloid, bone or the like.

5 An upper band 33 secured around the inner face of the waist 34 of the wearer's skirt, trousers or other garment 35 is provided with downwardly opening patch pockets 36 receiving the round upper ends 10 37 of the supports 32, whereby trousers, skirts or other garment, and a belt (not shown), if worn in the belt loops of the trousers, are supported on all sides a proper distance above the hips.

15 The upwardly open pockets 30 of the supporter adjoin the hip portions of the supporter on each side of the hip portions and are spaced apart thereby, and the downwardly open pockets 36 of the waist member 20 are arranged on this member so that when the waist member is operatively arranged on the wearer the pockets 36 are spaced apart and in alinement with the pockets 30 of the supporter, as seen in Fig. 3, the effect 25 being that the downward pressure of the supports 32 on the pockets 30 causes the hip portions of the supporter to bear down on and conformably fit over the hip of the supporter at the sides thereof and maintaining 30 the waist member and supporter spaced apart on the wearer.

Said supports 32 are furnished in sets of different length and are interchangeable to 35 provide different lengths of supports for different heights of waist lines of wearers and garments.

The pockets 30 and 36 are placed on the face of the abdominal support and the upper band 33 respectively, whereby said supporter and band serve as a cushion between the wearer and the ends of the supports 32.

40 The operation of the device is simple; and from the foregoing it is obvious that it may be applied in many different ways. A good 45 way of applying the support is first to put on the abdominal supporter and adjust the lacings and fasteners to position the edge 23 to conform to the top of the hips. The 50 supports 32 are then placed in the pockets 30, the garment is drawn up; then the upper ends of the supports are placed in the upper 55 pockets 36, and the garment is buttoned up or otherwise closed.

55 I claim as my invention:

1. In a garment support, the combination with a member secured to the garment at the waist line of the garment and extending around the garment, of a supporter of anatomical contour and consisting of right and left members having means cooperating between the members for adjustably securing the supporter around the wearer at the hips of the wearer; each of said right and left 65 members having front and rear end por-

tions of close material, a portion of ventilating material arranged intermediately of said front and rear end portions and having its lower edge arched to substantially fit over the hip of the wearer, and an elastic 70 portion joining said edge and extending over the hip; and means cooperating between the first above mentioned member and the front and rear end portions of said right and left members of the supporter for maintaining said member and said supporter spaced apart on the body of the wearer. 75

2. In a garment support, the combination with a member secured to the garment at the waist line thereof and extending around the garment and having downwardly open pockets, of a supporter of anatomical contour and consisting of right and left members having at the rear and front ends thereof means cooperating between the ends 80 for adjustably securing said ends together; each of said right and left members having front and rear end portions of canvas provided with upwardly open pockets, an open work fabric portion arranged intermediately of said canvas portions and having its lower edge arched to substantially fit over the hip of the wearer, and a portion of elastic webbing conformably joining said 85 edge and extending over the hip; and supports received at one of their ends in the pockets of the first above mentioned member and seated at their opposite ends in the pockets of the front and rear end portions 90 of the supporter for maintaining said member and said supporter spaced apart on the body of the wearer. 95

3. An abdominal supporter of washable fabric of anatomical contour adapted to fit around and over the hip to give comfort 105 and support to the abdominal region and comprising right and left members; each of said members comprising a front portion and a rear portion of canvas; an intermediate portion of ventilating openwork fabric 110 having its lower edge intermediately extending to near the upper edge of the member and arched to substantially fit over the hip and extend far down to the front and rear of the hip; and a hip portion of elastic 115 webbing fitting over and conforming to the hips and joining said lower edge from end to end.

4. In a garment support, the combination with a member secured to the garment at 120 the waist line thereof and extending around the garment in the waist line and having means for receiving upward pressure thereon, of a supporting band having right and left portions, each of the right and left portions having front and rear end portions made of close material connected by an intermediate hip-engaging portion made of open work fabric ventilating material contoured to fit conformably over the hip of 130

the wearer and having means for receiving downward pressure thereon adjoining the hip-engaging portion on each side thereof and spaced apart by the hip-engaging portion, means for connecting the front ends of said right and left portions, means for connecting the rear ends of said right and left portions, said upward pressure receiving means of the waist member being arranged 5 so that they are spaced apart from each other and in alinement with the downward pressure receiving means of said right and left portions when said waist member is operatively disposed and said hip-engaging 10 means engages conformably over the hips of the wearer, and means cooperating between said upward and downward pressure receiving means for exerting upward pressure on the waist member and downward pressure on the supporting member 15 and maintaining said members spaced apart on the wearer.

5. In a garment supporter, a supporting member consisting of right and left portions each having a front and rear end portion made of close material connected by an intermediate hip-engaging portion made of open work ventilating material, and means for receiving downward pressure thereon arranged on said supporting member on each side of said hip-engaging portions and adjoining each side of the hip-engaging portions.

6. In a garment supporter, in combination, a supporting member consisting of right and left portions each having a front and rear end portion made of close material connected by an intermediate hip-engaging portion made of open work ventilating material, means for receiving downward pressure thereon arranged on said supporting member on each side of said hip-engaging portions and adjoining each side of the hip-engaging portions, a member secured to the 45 waist line of a garment and extending in the waist line around the garment and having means for receiving upward pressure thereon, and means cooperating between said downward pressure receiving means of the sup-

porting member and said upward pressure receiving means of the waist member for exerting downward pressure on said supporting member for maintaining said members spaced apart on the wearer.

7. In a garment supporter, a band supported by the body of the wearer and consisting of right and left portions each having a front and rear end portion made of a canvas material connected by an intermediate hip-engaging portion comprising a strip of open work fabric ventilating material provided with a free upper edge and an inwardly curved lower edge and a strip of elastic material conforming at its upper edge to the inwardly curved lower edge of the strip of ventilating material and secured thereto and having a free outwardly curved lower edge.

8. In a garment supporter, in combination, a band supported by the body of the wearer and consisting of right and left portions each having a front and rear end portion made of close material connected by an intermediate hip-engaging portion comprising a strip of open work fabric ventilating material provided with a free upper edge and an inwardly curved lower edge and a strip of elastic material conforming at its upper edge to the inwardly curved lower edge of the strip of ventilating material and secured thereto and having a free outwardly curved lower edge, upwardly open pockets on the front and rear end portions of said right and left portions adjoining said hip-engaging portions on each side of said portions, a member secured to the waist line of a garment and extending in the waist line and having thereon downwardly open pockets, and flexible supporting strips received at one of their ends in said upwardly open pockets and received at their opposite ends in said downwardly open pockets.

Signed at New York in the county of New York and State of New York this 22nd day of July, A. D. 1925.

WILLIAM C. HERBERT.
